DESIGN FOR A PICTURE FRAME

Abraham C. Fuchs, New York, N. Y.

Application May 26, 1943, Serial No. 110,288

Term of patent 7 years

To all whom it may concern:

Be it known that I, Abraham C. Fuchs, a citizen of Poland residing at New York, in the county of New York and State of New York, have invented a new, original, and ornamental Design for a Picture Frame of which the following is a full, clear and exact description, reference being had to the accompanying drawing, forming a part thereof.

In the drawing:

Fig. 1 is a front elevational view of a picture frame, showing my new design.

Fig. 2 is a rear elevational view of the same.

Fig. 3 is a rear perspective view of the same.

I claim:

The ornamental design for a picture frame, as shown.

ABRAHAM C. FUCHS.
